UNITED STATES PATENT OFFICE.

JEREMIAH M. RICHARDSON, OF SALT LAKE CITY, UTAH TERRITORY, AS
SIGNOR OF ONE-THIRD TO JOSEPH L. HEYWOOD, OF SAME PLACE.

ROCK-DRILLING MACHINE.

SPECIFICATION forming part of Letters Patent No. 311,786, dated February 3, 1885.

Application filed June 7, 1884. (No model.)

To all whom it may concern:

Be it known that I, JEREMIAH M. RICHARDSON, a citizen of the United States, residing at Salt Lake City, in the county of Salt Lake and Territory of Utah, have invented certain new and useful Improvements in Rock-Drilling Machines; and I do hereby declare the following to be a full, clear, and exact description of the invention, such as will enable others skilled in the art to which it appertains to make and use the same.

The object of my invention is to provide a rock-drilling machine of simple construction, which shall perform more conveniently and economically than heretofore the functions of holding the drill against the rock to be operated upon, striking it a succession of heavy blows, rotating it gradually as it is struck, and feeding it forward into the hole which it produces. To this end I provide a frame capable of being conveniently and firmly fixed in position. Upon this is supported a sliding carriage which carries the drill, the latter being so mounted that it is free to move forward in said carriage for a limited distance when it is struck, while by a suitable engagement with the carriage, which prevents its being moved backward therein, it is held against the rock to be operated upon. The forward tendency of the carriage may be caused by a spring or by weights, as shown, which act constantly upon it; or by suitable devices it may be fed forward at will by hand. In the carriage is mounted a heavy hammer capable of being reciprocated forward or backward therein. It is normally held forward by a strong spring or by weights, if preferred, and when in that position bears against the rear end of the drill. A mechanism is provided whereby the hammer may be drawn or forced back, and then released to deliver its blow against the drill. By suitable devices this mechanism may also be made to turn the drill partially in the intervals between the blows.

It will be understood that, though particularly suitable to be operated by hand, the machine may be driven by steam or other power, if preferred, by the simple addition of a belt-pulley or other equivalent means of connection with said power.

For the purpose of clearly describing my

invention I have shown in the accompanying drawings a construction whereby it may be carried into effect, though other equivalent constructions may be used, if preferred.

Referring to said drawings, Figure 1 is a side elevation of the rock-drilling machine. Fig. 2 is a top plan view of the same, the hammer being shown as forced back and about to deliver its blow. Figs. 3 and 4 are detail views on a large scale.

The supporting-frame consists, as shown, of two parts, A and C.

A represents a rectangular frame, preferably of metal, supported in position for working by the hollow post B, to which it is hinged by a clamp, B', adjustable to any desired height on said post. The form of post shown is one adapted to be held between the roof and bottom of a tunnel or drift. Claws b² may be forced outward by screws b' to obtain the desired hold. The forward end of the frame A is supported by points a', which engage with the rock to be operated upon.

C is a carriage adapted to slide longitudinally upon the frame proper A. Suitable guides, c', hold it in position thereon. The carriage C carries the drill, the hammer, and the actuating machinery, and is moved forward to the work constantly by the weights E in an obvious manner, or at will by the hand-wheel d', according to the exigencies of the position of the machine. The wheel d' operates to turn a pinion, d², engaging with a stationary rack, a², secured to the frame A. If preferred, however, a simpler feed may be used, as shown in Fig. 3, consisting of a screw, d⁴, engaging with a thread in the frame A, and bearing directly against the rear of the carriage.

F is the drill, supported and guided in the frame or carriage C by means of the boxes f' and hinged caps f², which supports allow the drill a free forward and rotary play.

G is a spur or ratchet wheel, screwed to the drill near its rear end, and g is a collar similarly secured to the drill in front of one of its bearings, f' f², through which collar the forward tendency or movement of the carriage C is communicated to the drill.

g² is a collar secured to the drill adjustably, to facilitate the loosening of the drill if it

should become jammed in the rock. It will be observed that a drill of the ordinary character is quite suitable to receive these attachments and be mounted in the bearings $f' f^2$.
 5 A shaft, I, mounted on the carriage C transversely thereto, carries the hammer-operating cams H H. The shaft I may be rotated (in the direction of the arrow 1) either directly or by a train of gearing, J J, as shown, operated by hand-cranks K.
 By means of projections $h' h'$ on one of the cams H, adapted to engage with the gear-wheel G, the drill is given a partial rotation after each blow of the hammer. The drill is
 15 liable, occasionally, to become jammed in the rock and held so firmly that it cannot be rotated by the projections h' ; but another blow of the hammer may suffice to loosen it, and it is therefore desirable that means shall be pro-
 20 vided so that the projections h' may yield and not stop the operation of the machine. I have accomplished this by the devices illustrated in Fig. 4. The forward ends of the projections h' are beveled, so that under sufficient pressure, the wheel G being held immovable, said pro-
 25 jections will be forced backward into a recess in the cam H. A spring, h^3 , holds the parts h' normally in a position to engage with and rotate the wheel G, and is of sufficient strength
 30 to prevent the projections from yielding backward under any ordinary pressure. The strength of the springs h^3 may be regulated by means of screw-plugs h^4 , which close the rear ends of the recesses.
 35 L is the hammer, of suitable material, preferably metal, supported by the carriage C, so that it may easily be reciprocated therein. It is situated in line with the drill and below the plane of the shaft I.
 40 M is a strong spring, placed between the rear of the hammer and the carriage C. It is preferably kept in place by a rod, m', attached to said frame and passing loosely through an aperture in the hammer.
 45 The operation of the device is as follows, starting with the position shown in the drawings: A further rotation of the cams H H will disengage them from the front of the hammer, and the latter will be thrown against the rear
 50 of the drill with a force depending upon its weight and the strength of the spring M. The drill has in the meantime been held against the rock by the pressure of the carriage against the collar g. It will be noted that on account
 55 of the capability of forward movement relative to the carriage C, which the drill possesses, none of the shock of the hammer is transmitted to said carriage, but it is all expended upon the rock. After the blow is delivered
 60 the downward movement of the front end of the cam H having the projections h' causes the latter to engage with and partially rotate the gear-wheel G, and consequently the drill. The succeeding backward and upward move-
 65 ment of the same end of the cams forces back the hammer against the spring M for another blow.

The spring M may be flat or elliptical instead of spiral, as shown; or other equivalent devices for forcing the hammer forward may
 70 be substituted therefor without departing from my invention.

What I claim as of my invention, and desire to secure by Letters Patent, is—

1. In a rock-drilling machine, the combination of a stationary frame, a sliding carriage thereon, a drill mounted in said carriage, freely movable forward therein, and having a shoulder against the rear portion of which the carriage bears, and pressure devices, substantially as described, applied to the carriage for holding it against said shoulder with a yielding pressure, whereby the full force of the hammer is received by the drill without shock to the carriage, substantially as set forth. 75

2. In a rock-drilling machine, the combination of a stationary frame, a sliding carriage thereon, a drill mounted in said carriage, freely movable forward therein and having a shoulder against the rear portion of which the carriage bears, pressure devices, substantially as described, applied to the carriage for holding it against said shoulder with a yielding pressure, the sliding hammer supported in said frame independently of and in line with the drill, and devices for forcing the hammer against the drill, substantially as set forth. 90

3. In a rock-drilling machine, the combination of a stationary frame, a sliding carriage thereon, a drill mounted in said carriage, freely movable forward therein and having a shoulder against the rear portion of which the carriage bears, pressure devices, substantially as described, applied to the carriage for holding it against said shoulder with a yielding pressure, a reciprocating hammer, a cam for forcing back said hammer, and a ratchet-wheel rigidly secured to the drill, said cam being provided with a lateral projection engaging with the wheel, substantially as set forth. 100

4. In a rock-drilling machine, the combination, with the supporting-frame, of the drill having a ratchet-wheel, and a part, H, adapted to be moved past the periphery of said wheel, and having a yielding lateral projection adapted to engage with the wheel to turn the drill and to escape therefrom should said drill become jammed, substantially as set forth. 115

5. In a rock-drilling machine, the combination of the supporting-frame, the drill having a ratchet-wheel, the part H, having a lateral recess, projections h' , mounted in said recesses, and adapted to be carried past the periphery of said wheel and engage therewith, 120 and springs situated behind said projections to hold them out against ordinary pressure, substantially as set forth. 125

In testimony whereof I affix my signature in presence of two witnesses.

JEREMIAH M. RICHARDSON.
